CHARLES ROBERTS, OF LAKE VILLAGE, NEW HAMPSHIRE.

Letters Patent No. 89,170, dated April 20, 1869.

IMPROVEMENT IN TWISTING TUBES FOR SPINNING-MACHINES.

The Schedule referred to in these Letters Patent and making part of the same.

To all whom it may concern:

Be it known that I, CHARLES ROBERTS, of Lake Village, in the county of Belknap, and State of New Hampshire, have invented Improvements in Spinning-Machines; and I do hereby declare that the following is a full and exact description thereof, reference being had to the accompanying drawings, making part of this specification,

Figure 1 being a transverse vertical section of so much of a spinning-machine as is necessary to exhibit my improvements, and the mode of their application.

Figure 2, a central longitudinal section of my improved twister.

Figure 3, a front view of the feed-roller.

Like letters designate corresponding parts in all of the figures.

My improved twister consists of a short revolving tube, D, through which the roving, x, passes longitudinally, provided, at its lower or delivering-end, with two hollow "cone-points," f f, which spring together, in the line of the axis of the tube, and pinch the roving sufficiently to twist it, and at the same time allow the thread to be drawn along with a steady and even motion.

The tube composes its own journals, which revolve in bearings, a a, and it has a grooved pulley, d, by which the proper speed of revolution is imparted to it, in the same direction as the spindle revolves.

The hollow cone-points f f are preferably themselves elastic, by means of elastic shanks, h h, by which they

are attached, as at i i, to the tube D, but they might be rigid, and be pressed together by springs. And the force of the elasticity, if desired, may be adjustable, by any usual means. Any unessential variation in the form or arrangement of the points f f may be adopted.

Not only is this twister superior for its simplicity, cheapness, and efficiency, but it has a peculiarity which, in itself, is of great value, and which attains an object heretofore never reached. It is its slender-pointed form which enables it to reach within an eighth of an inch of the bearing-points of the draw-rollers F G, so that less than a quarter of an inch of the thread remains untwisted at any time, since all above this point is kept twisted by the cone-points, and all below the bearings of the draw-rollers is kept twisted by the spindle. Thus there is no chance for the breaking of the untwisted thread, or roving, nor for uneven drawing and variation in the size of the thread.

What I claim as my invention, and desire to secure by Letters Patent, is—

The hollow cone-points f f, held together by elastic pressure, arranged and operating substantially as and for the purpose herein specified.

The above specification signed by me, this 18th day of August, 1868.

CHARLES ROBERTS.
